Invenlor:

By Patrick L. McCauley
Mrs. Elvira -
M. L. M.

UNITED STATES PATENT OFFICE.

PATRICK L. McCUALEY, OF MANITOWOC, WISCONSIN.

NOTION CABINET.

Application filed March 28, 1927. Serial No. 179,064.

My invention relates to improvements in cabinets especially adapted for the display and sale of notions or the like, the object of the invention being to provide a simple and efficient construction of this character capable of being made economically from sheet metal.

Another object of the invention is to provide an improved shiftable partition for use in such cabinets.

Another object of the invention is to provide an improved display shelf arrangement for use in conjunction with such cabinets.

Another object of the invention is to provide an improved display rack arrangement for use in such cabinets.

Other objects will appear hereinafter.

In general the objects of the invention are attained by providing two separable sheet metal bodies arranged in stepped relation and divided by permanent longitudinal partitions and transverse shiftable partitions into a plurality of compartments arranged in tiers in stepped relation and adapted to contain and display notions for sale. Arranged on each of the longitudinal partitions is an index card rack of improved construction and arrangement adapted to receive index cards giving the prices of the articles in the various compartments, said index racks being arranged also to conceal and protect the edges of the partitions. The bodies thus provided are oppositely arranged back to back and serve to support and are in turn held together by means of a central display shelf arrangement. Display racks of improved construction are also detachably mounted under said shelf.

The whole is adapted and arranged to be supported on an ordinary counter or shelf.

The invention will be best understood by reference to the accompanying drawings forming a part of this specification and in which,

Fig. 1 is a perspective view of a cabinet embodying the invention;

Fig. 2 is an enlarged detail perspective view of one of a plurality of transverse partitions employed in the cabinet;

Fig. 3 is a top plan view of one of said transverse partitions detached;

Fig. 4 is a partial transverse section through the cabinet;

Fig. 5 is a section taken substantially on line 5—5 of Fig. 4, and

Fig. 6 is a perspective view of one end of

a display rack incorporated in the cabinet.

The preferred form of construction illustrated in the drawings comprises two separable similar sheet metal bodies 7 made in stepped relation, as shown, and adapted to be mounted back to back upon the top of an ordinary counter or table 8, as indicated in Fig. 1. Each of the bodies 7 is divided by a plurality of permanent longitudinal sheet metal partitions 9 and bottom plates 10 into shallow longitudinal troughs or divisions in stepped relation to each other, as shown. Arranged in each of the divisions thus provided is a plurality of shiftable transverse partitions 11, each made of a strip of sheet metal doubled centrally at 12 upon itself, as best shown in Figs. 2 and 3. Each part of each partition is provided at each end with outwardly and laterally extending spring wings 13 having outwardly extending guide beads 14 formed thereon as shown.

Reinforcing grooves 15 are formed at the junctures of the wings 13 with the body of the sheet 11 and whereby said junctures are reinforced against breakage at this point. Suitable guide grooves 16 are provided in the longitudinal partitions 9 and the ends of the compartments 7 for the reception and accommodation of the beads 14, and whereby said partitions are adjustably or shiftable mounted in said troughs. By this arrangement a simple and effective construction is provided, by means of which the partitions 12 may be economically manufactured and nicely held in various positions of adjustment.

Racks 17 and 17' are arranged at the upper edges of the partitions 9, each of said racks being provided at its lower edge with an upwardly turned lip or flange 18 as shown. The upper edges of the racks 17 are provided with enlarged beads 19, arranged and curved to rest over and protect and conceal the upper edges of the partitions 9 as best shown in Fig. 2. Corresponding beads 20 are arranged in the ends of the troughs, of a size and shape to correspond with the beads 19, so as to provide continuous smooth and similar upper edges to the troughs.

As shown, the beads 19 are made of sufficient height and opened at their bottoms to receive the upper edges of price index cards 21, the beads 19 being of greater depth than the lips 18, so that said index cards may be shoved upwardly in the beads 19 sufficiently to pass over the lips 18 in placing

said index cards in position. This arrangement furnishes a simple, effective and ornamental index card rack, whereby index cards may be readily provided to indicate the 5 prices of articles in the various compartments in the cabinet.

The index rack 17' at the upper edge of the innermost partition 9 in each body, is provided at its upper edge with a lip 19' 10 similar to the lip 18 at its lower edge, because the upper edge of the innermost partition 9 is not exposed and is covered by other parts of the cabinet which would interfere with such a bead as is provided at 15 the upper edges of the other index racks.

The innermost upper positions of the rack 17 are formed into supporting ledges 22, arranged adjacent each other when two of 20 said bodies are assembled, as shown. Supporting standards 23 in the form of sheets having reinforcing vertical beads 24 at their vertical edges are arranged at each end of the supporting ledges 22. The supporting 25 beads 24 are wrapped or coiled around reinforcing rods 25 which are extended at their lower ends to constitute dowels passing through suitable openings in the ledges 22 to hold the bodies 7 together, and also to hold the supporting standards 23 in position. 30

At its upper end, each of the standards 23 is provided with an inwardly turned securing flange 26 resting against the underside 35 of a display shelf 27 formed of sheet metal with depending side, and end flanges 28. A locking tongue 29 is pivotally mounted at each end of the shelf 27, to engage the corresponding flange 26 to lock the shelf in position on the end standards. This arrangement 40 constitutes a simple and effective construction for providing a display shelf and at the same time holding the bodies 7 in position.

Display racks are also provided under the 45 shelf 27. Each of said display racks is made from a single strip or sheet of sheet metal and comprises a vertical supporting wall 30' having an inclined supporting rack 30 extending outwardly and downwardly from 50 the upper edge thereof.

A supporting ledge 31 is provided as shown at the bottom of the rack 30, and an inwardly and downwardly extending supporting brace 32 is provided at the lower 55 edge of the ledge 31. A securing and stiffening flange 33 is arranged along the lower edge of the brace 32, as shown. A clamping bar 34 is arranged at each end and secured by bolts 35 to the ledges 22, as shown, said 60 clamping bar being arranged to engage the flanges 33 and hold the racks in position on the ledges 22, as shown, notches 36 being provided in the lower edges of the vertical walls 30' to accommodate the clamping 65 bars 34.

By this arrangement a simple and effective double display rack is provided for the cabinet on which various articles may be conveniently displayed.

While I have illustrated and described 70 the preferred form of construction for carrying my invention into effect, this is capable of variation and modification without departing from the spirit of the invention. I, therefore, do not wish to be limited to 75 the precise construction disclosed, but desire to avail myself of such variations and modifications as come within the scope of the appended claims.

I claim:

1. A display rack made of a single strip 80 of sheet metal bent to form a vertical wall, an inclined wall extending downwardly and outwardly from the upper edge of said vertical wall, a supporting ledge at the lower edge of said inclined wall, a supporting brace extending inwardly and downwardly from said ledge to substantially the level of the bottom of said vertical wall, and a securing flange at the lower edge of said 85 brace.

2. A double display rack construction comprising two separable display rack bodies, each consisting of a vertical wall, an inclined display wall extending outwardly and downwardly from the top of said vertical wall, a supporting ledge at the bottom of said inclined wall, a brace extending inwardly and downwardly from said ledge to substantially the level of the bottom of said vertical 95 wall, and a securing flange along the lower edge of said brace, there being registering notches in the lower edges of said vertical walls to receive a clamping bar.

3. In a cabinet having an elongated body, 100 one or more shiftable partitions in said body, each partition being provided at each end with spring metal wings, said wings extending along the walls of said body, and said wings and the corresponding sides of said 105 body being provided with interengaging beads and grooves slidably mounting said partitions in said body.

4. In a cabinet having an elongated body with guide grooves in the sides thereof; one 110 or more shiftable transverse partitions in said body, each partition being provided at each end with a spring metal wing projecting from the sides of said partition substantially perpendicularly thereto and resting 115 flat against the inner walls of said body, each wing being provided with a bead slidably engaging the corresponding groove in the corresponding side of said body.

5. In a cabinet having an elongated body 120 with guide grooves in the sides thereof; and one or more shiftable transverse partitions in said body, each partition being made of a sheet of metal doubled upon itself, each side 125 of said sheet at each end being provided with 130

a metal spring wing projecting from each side of said partition substantially perpendicularly thereto and resting flat against the corresponding side of said body, there being 5 outwardly extending beads on said wings slidably engaging the grooves in the sides of said body.

6. In a cabinet having an elongated body with outwardly extending guide grooves in 10 the sides thereof; one or more shiftable transverse partitions in said body, each partition being made of a sheet of metal doubled upon itself, each side of said sheet at each end being provided with an integral 15 spring metal wing projecting from the opposite sides of said partition substantially perpendicularly thereto and resting flat against the corresponding walls of said body, there being beads on said wings 20 engaging the grooves in the sides of said body, and reinforcing grooves at the junctures between said wings and the sides of said sheet.

7. A partition member of the class described formed of a single sheet of metal 25 doubled upon itself, each side of said sheet at each end being provided with an integral spring wing extending from opposite sides of said partition substantially perpendicularly thereto, the outer faces of said wings 30 lying substantially in the planes of the ends of the partitions, there being outwardly extending beads on each wing.

8. A partition member of the class described formed of a single sheet of metal doubled upon itself, each side of said sheet 35 at each end being provided with an integral spring wing extending from opposite sides of said partition substantially perpendicularly thereto, the outer faces of said wings lying substantially in the planes of the ends 40 of the partitions, there being outwardly extending beads on each wing; and reinforcing grooves at the junctures between said wings and said sides of said sheet.

9. In a cabinet having an elongated body; one or more shiftable transverse partitions in said body, each partition being provided at each end with a spring metal wing, said 45 wings resting flat against the walls of said body, and said wings and the corresponding 50 sides of said body being provided with inter-engaging beads and grooves.

10. A supporting standard comprising an upstanding sheet metal plate having a bead at each side and a reinforcing rod enclosed 55 in each bead, said rods projecting from one end of said plate to constitute positioning dowels, and a flange at the other end of said plate constituting a securing flange.

In witness that I claim the foregoing as 60 my invention, I affix my signature this 25th day of March, A. D. 1927.

PATRICK L. McCUALEY.
